UNITED STATES PATENT OFFICE

2,630,275

WINDING MACHINE

Winthrop L. Perry, Milford, N. H., assignor, by
mesne assignments, to Abbott Worsted Mills,
Incorporated, Wilton, N. H., a corporation of
New Hampshire

Application April 7, 1950, Serial No. 154,553

8 Claims. (Cl. 242—19)

1

This invention relates to that type of automatic winding machine in which the supply package of thread to be wound and the thread guide are both located beneath the winding bobbin, and constitutes an improvement upon United States Patent No. 2,426,168 granted August 26, 1947. It is generally desirable as in that patent and in United States Reissue Patent No. 22,492 and Patents Nos. 2,377,367 and 2,395,028 to locate the supply package beneath the winding bobbin so as to avoid complication or interference with the automatic bobbin-supplying mechanism which is located mainly above the level of the winding bobbin, and also so that the operator will not need to raise the heavy supply packages to an elevated position. It is moreover desirable as in Patent No. 2,426,168 to locate the thread guide beneath the winding bobbin so that the thread (as viewed in a plane transverse to the axis of the winding bobbin) can run upwardly, approximately in a straight line, to and through the thread guide and thence to the winding bobbin. As compared to the arrangements in Reissue No. 22,492 and Patents Nos. 2,377,367 and 2,395,028, this greatly reduces the frictional effect of the thread guide upon the running thread and the pull of the running thread upon the thread guide, and enables the thread to run with less variation in tension and allows the thread guide assembly to run more easily. The reduction of frictional action of the thread guide upon the thread is particularly desirable in the case of synthetic filaments and more especially of the type of plied yarn in which there is a difference between the characteristics of the different plies.

A principal object of the present invention is to improve automatic winding machines having this general relation of the supply package and thread guide to the winding bobbin, by improving the mechanism for effecting the transfer of the supply thread from a full wound bobbin over into association with a new empty bobbin to be wound.

The invention aims particularly to provide simple, reliable and long lasting thread-positioning mechanism adapted to carry thread into position to be associated with a new winding bobbin in cooperation with a thread guide located beneath the winding bobbin.

Other objects and advantages of the invention will be apparent from this specification and its drawings wherein the invention is explained by description of a preferred embodiment thereof.

In the drawings:

2

Fig. 1 is a plan view of the bobbin-changing mechanism of a traveling spindle automatic filling winding machine, showing one of the several winding units entering the bobbin-changing mechanism and showing fragments of winding units at further succeeding positions;

Fig. 2 is a front elevation, partly broken away, of one of the traveling winding units;

10 Figs. 3, 4, 5 and 6 are respectively a plan view, a front elevation, a bottom view and a right side elevation, of the thread guide assembly of a winding unit;

15 Fig. 7 is a vertical sectional view taken through the axis of rotation of the winding bobbin, showing the inner or base center and the rotatable thread positioning mechanism associated therewith, the thread-positioning mechanism having been rotated part way from its inactive position so that its thread-engaging hook is lowermost;

20 Fig. 8 is a front face view of the mechanism shown in Fig. 7;

Fig. 9 is a diagram taken from the same point of view as Figs. 2 and 8, showing successive positions of portions of a winding unit, corresponding to centerlines a—a, b—b, c—c and d—d of Fig. 1;

25 Figs. 9^a, 9^b and 9^c are diagrams in the nature of fragmentary right side elevations showing portions of a winding unit and its completed bobbin at the aforesaid lines, a—a, b—b and c—c; and

30 Fig. 9^d is a view similar to Figs. 9^a to 9^c showing a winding unit, in greater detail, at the line d—d.

Although some features of the invention may 35 advantageously be applied to winding machines in which tending mechanism attends to the changing of bobbins at only a single winding unit, or tending mechanism attends to the changing of bobbins of a plurality of winding units simultaneously, the invention has its fullest utility

40 when applied to a multiple unit machine in which a tending mechanism attends to the changing of the bobbins of a plurality of winding units in succession. In the preferred form of mechanism 45 shown, the relative travel, as between the plurality of winding units and the bobbin-changing tending mechanism, is brought about by moving the winding units in a procession past the tending mechanism as in the above mentioned

50 patents.

The winding machine to which the invention is shown as applied includes a plurality of traveling winding units 15 movable by means of a chain 55 18 upon tracks consisting of upper and lower

rails 16 and 17 respectively, in a closed counter-clockwise path of travel having straight side portions and semi-circular end portions as in United States Reissue Patent No. 22,492 and United States Patent No. 2,395,028.

Each traveling unit includes an upright frame element 15^a extending between the rails 16 and 17, with the winding mechanism of the unit carried at the top of the upright element 15^a, and with provision for holding the supply of thread to be rewound near the bottom of the unit.

Each winding unit is preferably individually driven by its own electric motor 19, such motor deriving its current through the frame of the machine and through suitable brushes contacting with stationary conductor bars 20 so as to wind thread onto an individual bobbin B as the winding unit travels around the machine. The conductor bars 20 extend completely around the machine excepting in the region of the automatic bobbin-changing mechanism.

The winding bobbin B is held between inner and outer chucks or rotatable hollow centers 24 and 25, the inner center 24 being rotated by the motor 19 to rotate the bobbin.

A bracket 50 is provided at the lower end of upright frame element 15^a, and any suitable package holder 55 mounted on the bracket 50 carries the supply package of thread P, which is typically a conical package of several pounds of thread wound on a paper core.

The thread T runs upwardly to the winding bobbin B through a suitable thread guide 102 (Figs. 2 and 9^d) and tension devices 104, 104 and through an open eye 107^c at the outer end of a swinging thread detector wire 107, to a traversing thread guide assembly 23.

The detector wire 107 preferably controls the motor 19 on the individual winding unit in known manner, so as to stop motor in the event of exhaustion of the thread. The detector wire 107 is thus shown in Fig. 2, as having an upper horizontal portion 107^a mounted in a bearing 109 and a rearwardly extending crank portion 107^b engaging the lower surface of a knock-off finger or latch member 107^c which is fast on a partially rotatable knock-off rod 107^d. In normal winding a notch 107^e in the latch member 107^c engages and holds to the right the upper end of a brush-controlling lever 108 corresponding to the arm 251 of Fig. 15 of United States Patent No. 2,426,168 to maintain the brushes of the winding unit in contact with the stationary conductor bars 20, for instance through brush-controlling mechanism such as is shown as controlled by the arm indicated at 463 in Figs. 16 and 17 of United States Patent No. 2,377,367.

The thread guide assembly 23 is preferably of the type that is frictionally mounted for sliding movement upon a traverse rod 23^c which is reciprocated with a short stroke of traverse by suitable traverse cam and linkage connections from the motor 19. During the winding of the bobbin the thread guide assembly 23 is progressively advanced along the rod 23^c, from near the base of the bobbin to near the tip of the bobbin by means of a stationary overhead abutment or cam similar to that described in U. S. Patent No. 2,362,455 which reacts upon an upstanding roller 42 upon the thread guide assembly, thus providing the filling type of winding on the bobbin.

This mode of advancing the thread guide assembly is preferred for use with the present invention in that it avoids need for any feeler engaging the winding bobbin and permits shift-

ing the thread guide to the region of the base center 24 while the winding bobbin is still held by the centers and without displacement of other parts of the winding unit.

The thread guide assembly includes certain parts similar to parts of the thread guide assembly in Patent No. 2,426,168, but simplified because of control of the progression by a stationary overhead abutment or cam as in Patent No. 2,362,455 and consequent elimination of feeler mechanism from the thread guide assembly.

Thus as best shown in Figs. 3 to 6 the thread guide assembly 23 includes an upper plate 61 and a lower plate 62 connected by vertical end pieces 63, 64 of fiber-composition material which frictionally engage the reciprocating traverse rod 23^c. The thread guide assembly also includes a tubular element 65 of fiber-composition material wrapped around the traverse rod 23^c and compressively held in frictional engagement therewith by an inwardly pressing spring jacket 66. An upstanding pin 80 carries the roller 42 by which the thread guide assembly is shifted in either direction along the traverse rod.

A rearwardly extending portion of the upper plate 61 carries a guide block 67 which is slidable beneath a guide bar 68 on the winding unit.

Thread guide 23^a is in the form of a wire bent to provide two parallel spaced portions beneath the winding bobbin, providing a narrow slit between them adapted to receive the thread. As shown in Fig. 2, the thread guide 23^a is located so that the thread can approach the winding bobbin by running upwardly from beneath the thread guide, through the thread guide and thence further upwardly to the winding bobbin. When viewed as in Fig. 2, that is, at right angles to the axis of the winding bobbin and path of reciprocation of the thread guide, the course of the thread to and through the thread guide is a straight line, the thread guide not causing any appreciable bend of the thread as viewed from this point of view but merely causing the requisite shifting of the thread back and forth for distributing it on the winding bobbin. This results in imposition of a minimum of tension on the thread by the thread guide, and in particular avoids frictional snubbing action upon the thread, so that there is no substantial tendency for the thread guide to cause the tension which exists in the thread approaching the thread guide to be multiplied in the thread beyond the thread guide.

A preferred construction which permits the thread guide 23^a to be easily and simply detachably held in place on the thread guide assembly is shown in Figs. 3 to 6. As there shown, particularly in Fig. 5, the lower plate 62 is open in its middle portion and notched to receive an upstanding portion of the wire 23^a and position this lengthwise of the thread guide assembly. The wire 23^a then extends up to the top plate 61, then over the top plate, and terminates in a laterally bent end portion 23^{aa} which lies under the rearwardly extending part of the upper plate 61. Thus the wire 23^a is resiliently held in place as shown, but by being slightly bent can be disengaged and removed, the opening in the bottom plate 62 permitting this removal.

As a winding unit enters the bobbin-changing mechanism of Fig. 1 from the left, the upstanding roller 42 of the thread guide assembly encounters an inclined stationary cam or guide element 44^a and the thread guide assembly is thereby shifted toward the base center 24 to carry the thread guide wire 23^a behind, or to the right of in Fig.

9a, the plane of the face of the base center 24, the wound bobbin thus far remaining in the centers 24 and 25.

Upon completion of this movement of the thread guide, the outer center 25 of the winding unit is retracted, at the position *a—a* by a crank arm 30 on the winding unit encountering a non-traveling abutment 31. The left end of this abutment is preferably in the form of a rotatable wheel 31^a adapted to ease the movement of the crank arm 30 onto the abutment 31. The wound bobbin then drops from the centers 24 and 25 onto a lower horizontal stationary plow plate 32 which extends along the path of travel of the winding units underneath their head portions. A generally vertical plate 35 on the winding unit then pushes the discharged bobbin along with the winding unit to the right end of the lower plow plate. A polished metal plate 32^a preferably overlies that portion of the lower plow plate 32 traversed by the discharged bobbins, so as to minimize the friction of travel of the discharged bobbins and minimize any tendency of the discharged bobbins to roll rather than slide.

Preferably, preparatory to discharge of the wound bobbin B from the centers 24 and 25 at the position *a—a*, a small additional length of thread is drawn through the tension devices 104, 104 by the eye 107^f of the thread detector wire 107. An inclined cam plate 120 mounted on the lower face of plate 32 is adapted to engage the detector wire 107 and plow it to the dotted line position shown in Fig. 9^d, thus drawing thread upwardly from the package P through the tension devices 104, 104. The additional thread thus provided facilitates the free dropping of the bobbin B from the centers, whereupon the thread moves the detector wire outwardly to a position such as shown in full lines in Fig. 9^d.

The run of thread which extends from the detector wire 107 to the thread guide wire 23^a extends past the inner edge of the lower plow plate 32, between this inner edge and the head portion of the winding unit. The inclined leading edge of the plow plate 32, first encountered by the thread as the winding unit enters from the left of Fig. 1, insures that this run of thread will not be caught and detained by the bobbin-changing mechanism.

Near the right end of the bobbin-changing mechanism, at position *d—d* as shown in Fig. 1, the winding unit reaches bobbin-feeding mechanism indicated at 40 which may be that of Fig. 21 of said Patent No. 2,377,367 at which an empty bobbin B' is held by swingable fingers 55 and 56 (Fig. 9^d), whereupon the outer center 25 closes upon the empty bobbin, forcing the base of this empty bobbin into the hollow base center 24, and thus causing this bobbin to be withdrawn from the bobbin-feeding mechanism.

An upper plow plate 53, at a level above the discharged bobbin, carries the cooperating blades of a cutter, blade 60 of which is pivoted and closed automatically at each passage of a winding unit by any suitable mechanism, for instance by the mechanism for closing the corresponding blade as shown in application Serial No. 103,242, filed July 6, 1949. As hereinafter explained, this cutter severs the thread between the new bobbin B' and the old discharged bobbin B. Following such cutting, the discharged bobbin B can drop off from the right end of the lower plow plate 32 into any suitable container or bobbin-arranging mechanism.

Position *a—a* of Fig. 9 and also Fig. 9^a illus-

trate the thread as extending up to the thread guide wire 23^a which is now behind or to the right of the plane of the face of the base center 24, and thence to the discharge bobbin. Positions *b—b*, *c—c* and *d—d* of Fig. 9 and the corresponding Figs. 9^b, 9^c and 9^d show the subsequent action in positioning the thread for engagement by the new bobbin.

The hollow center 24 of each unit, as shown in Fig. 7, is provided with a sleeve portion 24^a which is keyed to a shaft 24^b driven by the motor 19 of Fig. 1, and rotatable in a bearing 24^c in the casing 24^d of the head of the winding unit. A retaining ring 150 surrounds the sleeve portion 24^a of the center with a loose fit and is secured to the casing 24^d by screws 150^a.

Each unit is provided with a wheel or disk 151, having a flange 151^a, the wheel or disk 151 being rotatable on the retaining ring 150 and yieldingly urged in the clockwise direction in Fig. 8 by a coiled spring 152 contained within the flange 151^a. Spring 152 may for example have one of its ends held in a slot in the flange 151^a at 152^a in Fig. 8, and the other of its ends held by a pin 152^b secured to the retaining ring 150. A stud 154 on wheel 151 normally abuts against a resilient stop member 155 mounted on a plate 156 which is secured between the retaining ring 150 and the casing 24^d of the unit.

The outer face of wheel 151 carries an arm 159 spaced from the periphery of the center 24 and terminating in a radially outwardly extending thread-engaging hook or finger 160 which lies approximately flush with the plane of the face of the center 24.

The preferred form of mechanism for actuating the wheels 151 and hooks 160 of the several winding units includes a non-traveling rack 170 extending along the automatic bobbin-changing mechanism over the path of the wheels 151. To cooperate with such rack each wheel 151 is provided with widely spaced teeth 151^b extending only partially around its periphery.

A toothed wheel 151 of a unit, traveling to the right in Fig. 9 reaches the position *a—a* without any of its teeth engaging the rack 170. Slightly beyond position *a—a* the teeth of rack 170 begin and the teeth of wheel 151 are successively engaged by the teeth of the rack, rotating the wheel counterclockwise and bringing the hook 160 to a position approximately directly above the center 24. Following this rotation the last tooth of the wheel then slides along against a non-toothed holding portion 170^a of the rack, maintaining the hook as shown at positions *c—c* and *d—d* until the end of the holding portion of the rack is reached. Thereupon, with the wheel disengaged from the rack, its spring 152 returns the wheel to its inactive position such as shown at position *a—a*.

In the rotation of the wheel 151 its thread-engaging hook 160 engages with that run of the thread which extends from the thread guide to the discharged bobbin as shown in Figs. 9^b and 9^c and rotates around the center to carry the thread upwardly and across the center.

A preferred feature of the invention is that only one leg of the loop of thread that is formed by this upward motion of the hook is disposed across the center for engagement with a new bobbin, namely, that leg of the loop which extends from the hook 160 to the discharged bobbin. Because of the positions of the hook and thread guide relative to the plane of the face of the center, rotation of the hook disposes the other leg of the

loop, that is, the leg extending from the thread guide to the hook 160, out of position to be engaged by a new bobbin by progressively winding or wrapping this other leg of thread around the periphery of the center 24 as shown in positions b—b and c—c of Fig. 9 and Figs. 9^b and 9^c. The periphery of the center 24 is preferably dished, as best shown in Fig. 7, to retain the wrapped thread temporarily thereon.

The upper plow plate 53 assists in positioning the thread for engagement between a new bobbin and the center 24 by plowing the thread which extends from the hook 160 to the discharged bobbin over toward the center, the beginning of this plowing action being shown in Fig. 9^c.

As the unit approaches the position of Fig. 9^d, the thread extends across and in front of the face of the center, close thereto. At the position of Fig. 9^d the new bobbin B' is held by the swingable fingers 55 and 56 of the bobbin-feeding mechanism 40. A crank arm 30 which controls the outer retractable center 25 leaves the abutment 31 and the outer center closes upon the new bobbin, forcing into the hollow center the base end of the bobbin and the thread which has been disposed in front of the face of the center. The thread shown in dotted lines in Fig. 9^d as now within the center is gripped between the bobbin base and the center.

Shortly beyond the position of Fig. 9^d the thread extending from the new bobbin B' to the discharged bobbin B is guided by the edge of the upper plow plate 53 in between the fixed and movable blades of the cutter, and the movable blade 60 of the cutter is then closed to cut the thread, for example by suitable actuating linkage operated by the passing winding units similarly to the linkage shown for the purpose in application Serial No. 103,242, filed July 6, 1949. The thread guide and the edge of lower plow plate 32 maintain the thread which extends from the supply package to the thread guide out of the zone of action of the cutter.

At approximately the time the thread is cut, the member 160 returns to its inactive position, disengaging the thread. As in U. S. Patent No. 2,362,455 the thread guide assembly can then be shifted into position for the start of winding by means of a suitable stationary overhead inclined guide or cam.

As explained above, the two legs of the loop formed by the hook 160 are preferably kept separate and only one of these disposed in front of the center in position to be gripped between the bobbin and center. This has the advantage of avoiding leaving an unnecessary number of ends of thread extending out from between the base of the new bobbin and the center, and the possibility of fraying of these ends. This also has the further advantage of avoiding any entanglement or close proximity of the two legs of this loop, which would render it difficult then to separate the part to be cut by the cutter and the part extending from the thread guide to the center which is not to be cut.

It will be observed that while in the apparatus shown in U. S. Patent No. 2,426,168 a thread-positioning member, more especially a combined clamp and cutter, is arranged to act on the threads of the successive winding units to position the thread for engagement by the new bobbin, the machine shown in the present application provides an individual thread-positioning member traveling with each winding unit and effective automatically upon encountering the rack

170. This improved construction avoids any need for a thread-positioning member to be swung into and out of the path of the traveling winding units, and this materially facilitates rapid 5 passage of the winding units past the place where the thread-positioning operation takes place, by removing the limitations imposed by movement of a single thread-positioning member into and out of the path of the units.

10 Whereas the apparatus of U. S. Patent No. 2,426,168 employs a thread-positioning member swingable about an axis above the path of the traveling winding units, so as to be able to clear the passing units, the machine shown in the present 15 application provides an individual thread-positioning member rotatable about the bobbin-holding center, thus greatly reducing the length of arc through which the thread and the thread-positioning member are swung, making the action 20 easier, less abrupt, and more certain.

While the apparatus of Patent No. 2,426,168 acts to dispose the thread across the center by first cutting and clamping the thread and then carrying the clamped portions across the center, 25 the machine shown in the present application places the thread without depending upon such previous cutting and clamping. This avoids all tendency of the thread to be permanently pulled out from a clamp and cutter. This also avoids 30 dependence upon mere frictional holding of an end of the thread. In addition this improvement avoids any need for a rapid action of a cutter and clamp at an accurately timed point in the cycle of operation.

35 In the illustrated machine the thread is not cut until after it has been securely gripped between the base end of the new bobbin and the center, and the end of thread thus cannot be lost during the positioning operation. The cutting 40 operation of the cutter 60 can be relatively slow, and the cutter 60 can be relatively large, and no great accuracy of timing is required.

45 In addition to all of the foregoing, the present invention has the advantage of providing a very simple, compact construction of thread-positioning mechanism, cheap enough to be economical to apply to each of the many winding units of a traveling spindle winding machine. Since each 50 of these individual thread-positioning mechanisms is called upon to operate only once in each trip around the machine, its usable life can be expected far to exceed that of a thread-positioning mechanism which is called upon to act upon the thread of each winding unit in succession. 55 Also, if one such individual thread-positioning mechanism of the machine should fail, its winding unit can be readily removed for repair without disabling the machine as a whole.

60 I claim:

1. An automatic winding machine including a center for rotatably holding a winding bobbin and mechanism for supplying fresh bobbins to the center, a thread guide located beneath the winding bobbin so that thread can approach the winding bobbin by running upwardly from beneath the thread guide, through the thread guide and thence upwardly to the winding bobbin, means for discharging a wound bobbin downwardly from said center, a member engageable 65 with the thread which extends from the thread guide to the discharged bobbin and movable to carry a loop of thread upwardly to dispose at least a portion of the loop in position to be engaged between said center and a fresh bobbin supplied 70 to said center, and mechanism for severing that 75

leg of said loop of thread which extends from the fresh bobbin to the discharged bobbin after said fresh bobbin has been supplied to the center.

2. An automatic winding machine including a center for rotatably holding a winding bobbin and mechanism for supplying fresh bobbins to the center, a thread guide located beneath the winding bobbin so that thread can approach the winding bobbin by running upwardly from beneath the thread guide, through the thread guide and thence upwardly to the winding bobbin, means for discharging a wound bobbin downwardly from said center, a member engageable with the thread which extends from the thread guide to the discharged bobbin and movable to carry a loop of thread upwardly in such position as to dispose one leg of said loop in position to be engaged between said center and a fresh bobbin supplied to said center and the other leg of said loop out of position to be engaged between such fresh bobbin and the center.

3. An automatic winding machine including a center for rotatably holding a winding bobbin and mechanism for supplying fresh bobbins to the center, a thread guide located beneath the winding bobbin so that thread can approach the winding bobbin by running upwardly from beneath the thread guide, through the thread guide and thence upwardly to the winding bobbin, means for discharging a wound bobbin downwardly from said center, a member engageable with the thread which extends from the thread guide to the discharged bobbin and movable to carry a loop of thread upwardly in such position as to dispose that leg of said loop which extends from said member to the discharged bobbin in position to be engaged between said center and a fresh bobbin supplied to said center and the leg of said loop that extends from said member to the thread guide out of position to be engaged between said fresh bobbin and the center.

4. An automatic winding machine including a center for rotatably holding a winding bobbin and mechanism for supplying fresh bobbins to the center, a thread guide located beneath the winding bobbin so that thread can approach the winding bobbin by running upwardly from beneath the thread guide, through the thread guide and thence upwardly to the winding bobbin, means for discharging a wound bobbin downwardly from said center, and a member engageable with the thread which extends from the thread guide to the discharged bobbin and rotatable around the center to carry a loop of thread upwardly and dispose one leg of such loop in front of the face of the center while winding the other leg of such loop around the periphery of the center, out of position for engagement with a fresh bobbin.

5. An automatic winding machine including a center for rotatably holding a winding bobbin and mechanism for supplying fresh bobbins to the center, a thread guide located beneath the winding bobbin so that thread can approach the winding bobbin by running upwardly from beneath the thread guide, through the thread guide and thence upwardly to the winding bobbin, means for discharging a wound bobbin downwardly from said center, a member engageable with the thread which extends from the thread guide to the discharged bobbin and rotatable around the center to carry a loop of thread upwardly and dispose

in front of the face of the center that leg of the loop which extends from said rotatable member to the discharged bobbin, the machine including mechanism acting to position the thread which extends from the thread guide to said rotatable member so that a portion of such thread is wound around the periphery of the center, out of the way of a fresh bobbin.

6. An automatic winding machine including a center for rotatably holding a winding bobbin and mechanism for supplying fresh bobbins to the center, a thread guide located beneath the winding bobbin so that thread can approach the winding bobbin by running upwardly from beneath the thread guide, through the thread guide and thence upwardly to the winding bobbin, means for discharging a wound bobbin downwardly from said center, a member engageable with the thread which extends from the thread guide to the discharged bobbin and rotatable around the center to carry a loop of thread upwardly and dispose in front of the face of the center that leg of the loop which extends from said rotatable member to the discharged bobbin, the machine including mechanism acting to position the thread guide so that the leg of the loop which extends from the thread guide to said rotatable member is wound around the periphery of the center.

7. In an automatic winding machine having relative traveling motion between a plurality of winding units and a tending mechanism which is adapted to supply new winding bobbins to the winding units in succession; a rotatable thread-positioning member on each winding unit, said member being rotatable against a restoring force to position the thread of that unit for engagement with a new winding bobbin, and a member associated with the tending mechanism for rotating the several said thread-positioning members on the several winding units.

8. In an automatic winding machine having relative traveling motion between a plurality of winding units and a tending mechanism which is adapted to supply new winding bobbins to the winding units in succession; a rotatable thread-positioning member on each winding unit, a spring adapted to restore each said member to an idle position, a rack associated with the tending mechanism for rotating the several gears to a position to dispose the thread of the winding unit for engagement with a new winding bobbin, the rack having a holding portion effective to detain each gear in its last-named position as the winding unit encounters the bobbin-supplying mechanism, the thread-positioning member then being returned to an idle position by said restoring means.
